United States Patent Office

Des. 202,460
Patented Sept. 28, 1965

202,460

LAWN SPRINKLER

Ross E. Cornwell, Chicago, Ill., assignor to Sunbeam
Corporation, Chicago, Ill., a corporation of Illinois

Filed June 19, 1963, Ser. No. 75,427

Term of patent 14 years

(Cl. D91—1)

FIG-2

FIG. 1 is a perspective view of a lawn sprinkler embodying my design;

FIG. 2 is a side elevational view thereof;

FIG. 3 is a top plan view thereof;

FIG. 4 is a front end elevational view thereof; and

FIG. 5 is a rear end elevational view thereof.

Portions are omitted in FIGS. 2 through 5 for the convenience of illustration.

The dominant features of my design reside in the portions shown in full lines.

I claim:

The ornamental design for a lawn sprinkler, as shown and described.
